UNITED STATES PATENT OFFICE.

LYNWOOD R. SCHULER, OF WASHINGTON, DISTRICT OF COLUMBIA.

NOSTRIL-CLEANER.

1,326,616.

Specification of Letters Patent. Patented Dec. 30, 1919.

Application filed August 21, 1919. Serial No. 319,045.

To all whom it may concern:

Be it known that I, LYNWOOD R. SCHULER, a citizen of the United States, residing at Washington, in the District of Columbia, 5 have invented certain new and useful Improvements in Nostril-Cleaners, of which the following is a specification.

This invention relates to a nostril cleaner.

One object of the present invention is to 10 provide an instrument of the nature stated, embodying among other characteristics, an instrument particularly designed for daily nostril cleaning purposes.

Another object resides in the provision of 15 an instrument particularly designed for ready insertion into and removal from the nostril for the free and easy removal of accumulations in the nostril.

Another object resides in the provision of 20 an instrument which is not only serviceable by grown persons enjoying normal health, but designed for the removal of accumulations of ill persons and infants, to obviate the possibility of stoppage in the nostril in- 25 cident to accumulations.

The instrument is of such a nature that it may have a dual function, in that it is efficient and practical in the performance of the aforesaid functions, but it is equally ap- 30 plicable for use in the application of liquids, salves or other medicants to one's nostrils.

With these and other objects in view, the invention consists in the construction and novel combination of parts hereinafter 35 fully described, illustrated in the accom- 40 panying drawings and pointed out in the claims hereto appended, it being understood that various changes in the form, proportion, size and minor details of construction, 45 within the scope of the appended claims, may be resorted to without departing from the spirit of the invention or sacrificing any 50 of the advantages thereof.

In the drawing, in which like numerals 55 of reference designate corresponding parts:

Figure 1 is a side elevation of a nose 60 cleaning device constructed in accordance with this invention.

Fig. 2 is an end elevation of the same, the 65 tapered threaded cleaning portion being indicated in dotted lines.

In the accompanying drawing, in which is illustrated the preferred embodiment of the invention, the nose cleaner, which may 70 be constructed of any suitable material, is

preferably made of rubber sufficiently stiff to effect a removal of the accumulations of the nose and at the same time possessing sufficient flexibility to enable it to readily adjust itself to the general configuration of 60 the nasal passage without injuring the walls thereof.

The instrument may comprise a shank 1 and a tapered cleaning portion 2. The shank 1, which constitutes a handle or finger 65 piece, is preferably smooth and cylindrical, but it may be of any other desired configuration, and may be provided with any suitable exterior surface to facilitate accurate handling and proper application of 70 the instrument.

The tapered nose cleaning portion consists of a central tapering core 3 and a spiral rib 4 surrounding the core and gradually decreasing in diameter from the shank 1 to the outer end 5 of the instrument. The spiral rib has a smooth outer edge 6 to avoid injury to and irritation of the walls of the nasal passages. While not essential, the said spiral rib may be recessed or undercut 80 at the side faces at 7 to provide outer cleaning portions adapted to effect a ready removal of the accumulations of the nose and also to form transversely enlarged channels or grooves 8 between the flanges for conveying 85 away the accumulations and also for containing liquid for softening the accumulations or for treating affections of the nose. When the spiral cleaning portion is immersed in water or other liquid or in a salve, 90 a quantity of the same will be retained in the spiral groove for application to the nostril. Several applications may, of course, be made to secure the desired application of the liquid to the nose, if the instrument be used 95 for medicinal purposes.

What is claimed is:—

1. A nose cleaner including a relatively long cleaning portion flexible to conform to the contour of the nasal passage and provided with means for removing accumulations from the nose. 100

2. A nose cleaner provided with a threaded nose cleaning portion arranged to remove accumulations from the nose, said 105 cleaning portion being relatively long and tapered throughout its length and flexible to conform to the contour of the nasal passage.

3. A nose cleaner provided with a thread- 110

ed nose cleaning portion having a spiral flange for the removal of accumulations from the nose, said flange being provided with a smooth relatively broad outer spiral edge, and being recessed or undercut at opposite sides.

4. A nose cleaner comprising a handle

portion and a tapered nose cleaning portion tapered from one end to the other and consisting of a tapering core, and a spiral ele- 10
ment surrounding the tapering core.

In testimony whereof I affix my signature.

LYNWOOD R. SCHULER.
